UNITED STATES PATENT OFFICE

WILLIAM GEORGE, OF LIBERTY, NEW YORK

MATTRESS OR CUSHION COVERING

Application filed April 30, 1929. Serial No. 359,379.

This invention relates to the art of manufacturing mattresses and cushions, and has more particular reference to a casing or covering for a mattress or cushion.

The primary object of the invention is to provide a mattress or cushion covering so constructed as to be very sanitary, to eliminate the usual depressions and holes produced by stitching the edges of coverings by hand or by the use of machines as is now employed.

In attaining the result as above enumerated my improved covering is so formed as to be free of depressions or holes in the upper or lower faces, near the edges and likewise be free from creases, or places where vermin may congregate, dust and dirt collect, as well as to prevent the formation of holes in the fabric resulting from the process of manufacture, which holes are undesirable since they permit dust to be expelled from the mattress or cushion.

Another very important object of the invention is to provide a mattress or cushion covering wherein the time and course of manufacturing is substantially reduced. Such result is attained by so forming the covering as to require stitching only twice, which stitching is necessary to unite the top and bottom portions of the covering with the central portion, the said stitching not only holding the sections together as above mentioned, but also includes a means for stitching the stiffening material for the covering.

Other objects and advantages of the invention will become apparent from a study of the following description, taken in connection with the accompanying drawing, wherein:

Figure 1 is a fragmentary transverse sectional view taken through my improved covering.

Figure 2 is a fragmentary end view of the same.

The present invention comprehends a mat-

ress or cushion consisting of a covering in the form of a casing, and which covering is adapted to receive suitable filling materials, whereby the covering or casing together with the filling material constitutes the entire 50 cushion or mattress as the case may be. For the sake of clarity then, I shall refer to the covering generally as a casing, and designate the same likewise generally, by the reference character A.

In so forming the casing I employ a strip of sheet felt, cotton wadding, sheet hair or other stiffening material, designated by the reference character 5, and as is usually employed in filling mattresses or cushions or in general padding operation. The felt, padding, etc. designated as at 5 constitutes a stiffening means for the mattress or cushion and consequently consists of a strip of sufficient thickness, and cut to a proper width to produce the desired height of the boxing or casing A. To the outer face of the reinforcing or stiffening strip 5 is placed a strip of material 6, which material 6 may be in the form of ticking, as in the case of a mattress, or of any other suitable, desired, fancy or plain material, as would be employed in the making of a cushion. The strip 5 of stiffening material and the strip 6 which as before mentioned may be of any desired material 65 constitutes the boxing or sides and ends of the cushion or mattress. A top covering 7 being preferably of a material corresponding to the material 6 is stitched adjacent its marginal edges to the fabric 6 and reinforcing strip 5 as at 9.

To the opposite marginal edges of the reinforcing member 5 and fabric 6 is also secured the bottom covering 10, as at 11, and as is apparent from the drawing in exactly 85 the same manner as the cover 7. When assembling the cover 7, and the bottom covering 10 to reinforcing member 5 and fabric 6, it is to be noted that the material comprising the top and bottom to the material 6 and 90

stiffening element 5, the several parts are sewn inside out, and thus it will be seen when the assembled casing is turned right side out for the purpose of filling, no threads or stitching show, and any holes made by stitching are covered by reversing the material constituting the top 7 and bottom 9 as at 8, as clearly illustrated in Figure 2 of the drawing. Thus is provided the completed casing, and it is 10 to be understood of course when the casing is so completed that a small section of some portion of the casing is left unsewn, or otherwise provided with inspection or filling slits through which may be introduced the filling 15 material for the main body of the mattress or cushion. Such slits may be cut through the casing at the side or end of the boxing at any desired width before the top and bottom covering 6 and 7 respectively are attached, or such slits may be cut and finished after all sewing of the casing is completed, or in any other way desired. Such filling slits may be closed either by means of buttons, lacings, or zipper strips, sewing or in 20 25 any other manner.

It is also to be noted that in so forming my improved casing the reinforcing strip 5, the fabric 6 and the ends of the coverings 7 and 10 require but two stitching operations, namely a stitching for securing the cover, the side, and end members or boxing 6 and reinforcing strip 5, and a stitching for securing the reinforcing strip, side and end members or boxing and the bottom 10 as clearly shown in the 30 35 drawing.

From the foregoing then it will be seen that I have provided an improved casing or covering for mattresses and cushions which is very simple in construction, can be manufactured in a relatively short time, and at a substantially small cost, will be thoroughly efficient and sanitary, eliminating any place where vermin, dust or dirt may collect, and which is otherwise thoroughly efficient and capable for obtaining the result for which it 40 45 is designed.

While I have herein described the invention somewhat in detail, it is to be understood that the invention is susceptible to changes fully comprehended by the spirit of the invention as herein described and the scope of the appended claim.

Having thus described the invention, what I claim as new and desire to secure by Letters Patent is:—

A covering for a mattress or cushion comprising a top member and a bottom member, a boxing for connecting said top and bottom members, said boxing constituting sides and 50 55 ends for the covering, said boxing comprising an outer strip of fabric and an inner strip of reinforcing material corresponding in length and width to the length and width of said outer strip, said top and bottom members at their marginal edges having portions

folded inwardly against the adjacent sides and ends of the box, the free edges of the inwardly folded portions terminating inwardly from the free edges of the said adjacent sides and ends of said boxing, and a single row of 70 stitching securing the said inner and outer strips of said boxing together, and securing the inwardly folded portion to said sides and ends of said boxing inwardly of the free edges of the said inwardly folded portions of said 75 top and bottom members.

In testimony whereof I affix my signature.
WILLIAM GEORGE.
